UNITED STATES PATENT OFFICE

JOHN NESE, OF NIAGARA FALLS, NEW YORK

ASH SIFTER

Application filed July 15, 1931. Serial No. 551,026.

This invention relates to ash collectors for stoves and furnaces, and it has particular relation to a collector for clinkers and ashes that is adapted to be employed in various types and sizes of stoves and furnaces.

In utilizing fuel such as coal in furnaces it is necessary to provide facilities for moving the ashes and clinkers, etc., and it has been common practice to utilize a box for this purpose into which the ashes fall or into which they are shoveled. A considerable amount of fuel may be recovered from the ashes by sifting them and returning the combustible substance to the furnace. Ordinarily this substance is in the form of clinkers.

It is the purpose of this invention to provide a clinker and ash collector that can be included in a furnace and by which the ashes and clinkers can be satisfactorily separated. By employing this improved collector the ashes may be shaken from the clinkers as soon as they have fallen from the furnace grate and the clinker collector can be removed independently of the other elements of the construction, and the clinkers may then be returned to the furnace for further combustion. Likewise the ash collector functions in conjunction with the sifter and can be removed independently. Moreover the entire structure of the clinker and ash collector can be removed as a unit and it is of such structural character that the dimensions may be varied in order that it may be installed in various types and sizes of furnaces.

For a better understanding of the invention reference may now be had to the accompanying drawings forming a part of this specification, of which:

Fig. 1 is a fragmentary elevation of a furnace having a clinker and ash collector embodying the invention disposed therein;

Fig. 2 is a perspective of a clinker and ash collector;

Fig. 3 is a longitudinal section taken substantially along the line III—III of Fig. 1;

Fig. 4 is a fragmentary perspective of an ash box; and

Fig. 5 is a fragmentary perspective taken substantially along the lines V—V of Fig. 3.

In practicing the invention a frame 10 is

inserted into a conventional stove or furnace 12 that has an upper door 13 through which fuel, such as coal, is supplied and a lower door opening 14 through which the frame is inserted. An ordinary swinging door 16 having hinges 17 supporting it upon the furnace is provided with a central draft opening 18.

The frame 10 is provided with front and rear straps 22 and 23, respectively, which have slots 24 therein for receiving adjustable bolts 25 that are secured to extensions 27 and 28 at the upper ends of the straps. Upper and lower guides 29 and 30 extending horizontally from one end of the frame to the other are rigidly secured to the extensions 27—28 and straps 22—23, respectively, and are in the form of angle bars. Reinforcing bars 31 extend transversely of the frame and connect the opposite end portion of the guides 29. Upper end portions 32 of the extension are bent or flared outwardly for the purpose of supporting oppositely inclined plates 33 that have slots 34 therein for facilitating the adjustment thereof in various positions by properly manipulating screws 36 inserted through the slots and secured to the upper end portions 32. At the rear end of the frame a curved inclined plate 37 constituting substantially a continuation of the plates 33 is secured to the rear extensions 28, and to an ear 38 of a reinforcing strip 39 that extends from the front extensions 27 to the rear extensions 28 and has a curved rear portion 40 from which the ear projects. Suitable connections 42 support this strip upon the extensions 27 and 28.

An ash box 43 having a handle 44 secured to the front end thereof is slidably disposed upon the lower guides 30 and is provided with a bail 46 that is pivoted to brackets 47 secured, as indicated at 48, to the inner sides of the central portion of the box walls. Lugs 49 are provided on the bracket to prevent tipping of the box when it is lifted by the bail.

Likewise an ash sifter 50 shaped substantially similarly to the ash box is slidably disposed upon the upper guides 29 and is provided with a handle 52 to facilitate with-

drawing it from the frame 10. Another handle 53 which is pivoted as indicated at 54 to the sifter is normally adapted to extend through the opening 18 of the furnace door, and by properly manipulating this handle the sifter can be reciprocated upon the guides without opening the door of the furnace. A bail 56 similar to the bail 46 is pivoted centrally of the sifter.

10 The lower portion of the sifter has inwardly turned flanges 57 and a section of metallic mesh material 58, constituting a greater portion of the bottom of the sifter, has its edges confined firmly between the flanges 57 and a metallic strip 59 that is substantially complementary to the flanges 57 and is disposed about the inner bottom corners of the sifter. Suitable connections 60 extending through the flanges 57 and through the strip 59 clamps the mesh material therebetween. It will be observed that the front portion of the strip 59 is in the form of a relatively large plane or plate 62 which prevents ashes from falling so far forwardly as to be spilled outside the front of the ash box when the sifter is reciprocated. It has been found that advantageous results can be obtained by employing expanded metal as the mesh material 58 for shifting the ashes.

20 30 From the foregoing description it will be apparent that the frame including the ash boxes and sifter can be inserted as a unit into furnaces of sizes obtaining in ordinary constructions and the plate 33 can be adjusted laterally and upwardly by manipulating the screws 36 in the slots 34. Thus the ashes and clinkers that might otherwise drop outside the frame can be deflected into the sifter. Likewise the height of the frame 40 10 can be adjusted by properly manipulating the adjustable bolt 25 in the slots 24. Clinkers and ashes falling from the furnace into the sifter 50 can be agitated by forcing the handle 53 inwardly and outwardly to reciprocate the sifter, thereby causing the ashes to fall into the ash box 43 while the clinkers remain in the sifter. Then the box of ashes may be removed separately, and likewise the sifter containing the clinkers can be withdrawn and the clinkers deposited in the furnace for further burning. As indicated previously the entire sifting operation can be performed without opening the door of the furnace.

50 55 Although only one form of the invention has been shown and described in detail it will be apparent to those skilled in the art that the invention is not so limited but that various changes may be made therein without departing from the spirit of the invention or from the scope of the appended claims.

What I claim is:

1. An ash collector comprising upper and lower removable compartments, a frame hav-

ing guides therein for receiving the compartments, and adjustable members in the frame for varying the width and height of the latter.

2. An ash collector comprising a frame, 70 extensible corner members for varying the height of the device, members extensible transversely of the frame for varying its effective width, a plurality of sets of guides mounted upon the extensible corner members, an ash sifter mounted upon one set of the guides, and an ash box mounted upon another set of the guides. 75

3. An ash receiving device comprising a frame, relatively slidable members included 80 in the frame, means for securing the relatively slidable members in various positions of adjustment to vary the distance from one side of the frame to the other, a plurality of sets of guides in the respective slidable members of the frame, an ash sifter supported by one of the sets of guides, and an ash box supported by another set of the guides. 85

4. An ash receiving device comprising a frame, relatively slidable members included 90 in the frame, means for securing the relatively slidable members in various positions of adjustment to vary the distance from one side of the frame to the other, said frame including other members adjustable transversely of the direction of adjustment of said 95 slidable members, guides mounted in the respective slidable members of the frame, an ash sifter supported by one of the sets of guides, and an ash box supported by one of the sets of guides. 100

5. An ash receiving device comprising a frame, relatively slidable members included 105 in the frame, means for securing the relatively slidable members in various positions of adjustment to vary the distance from one side of the frame to the other, a plurality of sets of guides mounted in the respective slidable members of the frame, an ash sifter supported by one set of guides, and an ash box supported by another set of guides, said 110 ash sifter having a bottom portion composed of expanded metal.

6. An ash receiving device comprising a frame, relatively slidable members included 115 in the frame, means for securing the relatively slidable members in various positions of adjustment to vary the distance from one side of the frame to the other, a plurality of sets of guides mounted in the respective 120 slidable members of the frame, an ash sifter supported by one set of guides, and an ash box supported by another set of the guides, said ash sifter having a bottom partially of expanded metal and partially of sheet 125 metal.

7. An ash receiving device comprising a frame, relatively slidable members included 130 in the frame, means for securing the relatively slidable members in various positions of

adjustment to vary the distance from one side of the frame to the other, sets of guides mounted in the respective slidable members of the frame, an ash sifter supported on 5 one set of guides, an ash box supported by another set of guides, said ash sifter having its bottom composed partially of expanded metal and partially of sheet metal, and a handle extending from the sifter to facilitate reciprocating the latter upon the guide.

8. An ash receiving device comprising a frame, relatively slidable members included in the frame, means for securing the relatively slidable members in various positions of 15 adjustment to vary the distance from one side of the frame to the other, a plurality of sets of guides mounted in the respective slidable members of the frame, an ash sifter supported by one set of guides, an ash box supported 20 by another set of guides, said ash sifter having a bottom portion composed partially of expanded metal and partially of sheet metal, and a handle pivoted to a portion of the sifter adjacent the sheet metal to facilitate reciprocating the sifter upon the guide.

9. An ash collector comprising a frame, relative slidable members included in the frame, means for securing the relatively slidable members in various positions of adjustment to vary the distance from one side of the frame to the other, a plurality of sets of guides mounted in the respective slidable members of the frame, an ash sifter supported by one set of guides, an ash box supported 35 by another set of guides, and bails secured to the sifter and box respectively to facilitate their removal from the frame.

10. An ash collector comprising a box-like frame, upright members at the corners of the frame having slots therein, extensions upon the upright members, means in the slots for adjusting the extensions with respect to the upright members, said extensions having outwardly bent portions, plates mounted upon 45 the outwardly bent portions, means for adjusting said plates toward and away from each other to vary the effective width of the frame, an ash sifter having a mesh bottom slidable upon the extensions, and an ash receiving box slidably mounted upon the upright members.

11. In a furnace having an ash collecting space and a door having a draft opening therein secured to the furnace, a frame disposed within the furnace, guides in the frame, an ash sifter reciprocable upon the guides and removable from the frame, a handle secured to the sifter and normally extending outwardly from the draft opening of the furnace door to facilitate shaking of ashes in the sifter without opening the furnace door, and an ash box slidably mounted in the frame to receive ashes shaken from the sifter.

12. In a furnace having an ash collecting space therein and a door having a draft open-

ing therein secured to the furnace, a frame disposed in the furnace, relatively slidable members in the frame for changing the dimensions of the frame with respect to its height and width, guides in the frame, 70 an ash sifter reciprocable upon the guides and removable from the frame and furnace, a handle secured to the sifter and normally extending outwardly through the draft opening of the furnace door to facilitate shaking of 75 ashes in the sifter without opening the furnace door, and an ash box slidably mounted in the frame to receive the ashes shaken from the shifter.
